FRANZ FRIEDERICH KULLRICH, OF BERLIN, PRUSSIA. *

Letters Patent No. 95,915, dated October 19, 1869.

MUSICAL PICTURE-CASE.

The Schedule referred to in these Letters Patent and making part of the same.

To all whom it may concern:

Be it known that I, FRANZ FRIEDERICH KULLRICH, of Berlin, in the Kingdom of Prussia, have invented a new and improved Instrument for Combined Audible and Visible Display; and I do hereby declare that the following is a full, clear, and exact description thereof, which will enable others skilled in the art to make and use the same, reference being had to the accompanying drawings, forming part of this specification.

Figure 1 represents a plan view, partly in section, of my improved instrument for combined audible and visible display.

Figure 2 is a vertical section of the same, the plane of section being indicated by the line $x x$, fig. 1.

Figure 3 is a detail transverse section of the same, the plane of section being indicated by the line $y y$, fig. 2.

Similar letters of reference indicate corresponding parts.

This invention relates to a new combination, with a music-box, of an apparatus for displaying, through a suitable opening, a series of pictures in succession, so that whenever the music is played, the panorama will be in motion.

The invention consists chiefly in the application, to a music-box, of an additional roller, parallel to that one by which the music is produced, and in hanging an endless band around said two rollers, so that said band is moved by the rotation of the music-roller, to display pictures that are on said band, in succession through a suitable aperture of the case which encloses the whole mechanism.

A, in the drawing, is the music-roller or drum, which is hung in a frame, B, and connected, by gear-wheels $a a$, with a main-spring in a case, C, so that by means of the said spring, the drum A can be revolved.

Upon the periphery of the drum are set pins $b b$, which, as the drum is revolved, strike against and elevate, in the requisite succession, the reeds D D, by which the music is produced.

The drum may be longitudinally adjustable in its bearings, as in all music-boxes, for the purpose of producing different chimes.

E is a lever, for locking the drum after a chime has

been played. It is thrown into a notch or indenture in the end of the drum by a spring, e, and can, by a suitable lever, F, or by hand or otherwise, be moved or held away from the same.

G is a roller, hung in a sliding frame, H, some distance from and parallel with the drum A.

The frame H is, by springs $d d$, drawn away from the drum. The drum and roller are of equal diameters.

I is an endless belt or band, placed around the roller G and drum A.

To the outer face of this belt are painted, printed, or otherwise applied, pictures of suitable kind.

The springs d serve to hold the band tense on the roller and drum.

The whole mechanism is enclosed in a case, J, which may be in form of a photographic album, ladies' work-box, or other suitable device. In said case is an opening, e, through which one of the pictures on the band may be seen. When the drum is in motion, the band will also be turned, and the pictures on it will pass in succession under the aperture e, so as to be displayed in proper order.

The apparatus produces thus a moving panorama, together with music of suitable kind.

Having thus described my invention,

I claim as new, and desire to secure by Letters Patent—

1. The endless band I, carrying the pictures, in combination with the drum A of a music-box, all arranged so that the band is moved when the music is in action, as set forth.

2. The roller G, held by springs d , away from the music-drum A, for the purpose of keeping the band tense, as specified.

3. The case or box J, containing a music-box and picture-belt, and provided with an aperture, through which the pictures are displayed successively while the music is in action, as set forth.

The above specification of my invention signed by me, this 10th day of August, 1869.

FRANZ FRIEDERICH KULLRICH.
